CLAIM

The ornamental design for a desk calendar pad, as shown and described.

DESCRIPTION

FIG. 1 is a perspective view of a new and ornamental desk calendar pad;

FIG. 2 is a front elevation view thereof;

FIG. 3 is a top plan view thereof;

FIG. 4 is a bottom plan view thereof;

FIG. 5 is a side elevation view thereof, the opposite side being a mirror image thereof; and,

FIG. 6 is a rear elevation view thereof.

The broken line showing of a calendar in FIGS. 1 and 2 are included for the purpose of illustrating environmental structure and forms no part of the claimed design. The broken lines seen on the surface of the claim are understood to represent stitching.
